CLAIM

The ornamental design for a charging station for electric vehicles as shown and described.

DESCRIPTION

FIG. 1.1 is an elevated front, facing view of our new design for a charging station for electric vehicles;

FIG. 1.2 is an elevated right side view thereof;

FIG. 1.3 is an elevated left side view thereof;

FIG. 1.4 is an elevated rear view thereof;

FIG. 1.5 is a top, left facing perspective view thereof;

FIG. 1.6 is a bottom plan view thereof; and

FIG. 1.7 is a top plan view thereof.
